SCANNING RECEIVING SYSTEM

Warren H. Bliss, Orono, Maine, assignor to Radio Corporation of America, a corporation of Delaware

Application October 10, 1942, Serial No. 461,526

18 Claims. (Cl. 250—20)

1

This invention relates broadly to apparatus for scanning a given frequency band of the radio spectrum, locating any new signal which appears therein, and controlling a device for making a record of such a signal.

In monitoring the radio spectrum for enemy and illegal stations, a transmitter which suddenly goes into action, sends a short message at high speed, and then shuts down quickly is very hard to detect.

An object of the present invention is to provide an improved method of and apparatus for detecting the signals from such unknown stations, by means of which the probability that a new station will start up in such a position in a band being scanned that it will be missed by normal signal hunting is decreased to a large extent.

In brief, the present invention employs a scanning receiver for detecting telegraph stations within the range of frequencies scanned by the receiver and recording the signals therefrom. For accomplishing this, there is provided a superheterodyne receiver which is swept or tuned rapidly over a given band of frequencies by means of a sweep device. The output of the receiver is arranged to be in the form of keyed tone whose modulations correspond to the modulations of the received signals. This keyed tone is supplied to a comparator device in which the signals of the known stations in the band of frequencies scanned by the receiver are neutralized or blanked out, so to speak, by locally generated pulses. To achieve this result, there are provided as many local blank-out pulse generators as there are different known stations in the band to be scanned. Thus, the presence of a new signal suddenly appearing in the frequency spectrum being scanned will have no compensating or blank-out pulse and can be registered on a short loop of magnetic tape which is exactly two sweep cycles in length. This new signal from an unknown station can then be continuously recorded by means of a second receiver whose tuning is automatically adjusted by a motor control circuit to the particular position in the frequency band being scanned in which the new signal appears. In order to prevent the second receiver from responding to noise pulses which are random in nature and time of appearance, the motor control circuit for the second receiver is controlled by a comparator device. This comparator device will enable the motor control circuit to function provided the new signals are repeated during consecutive sweeps of the scanning superheterodyne receiver. So far, the apparatus de-

2

scribed above is in accordance with my copending application Serial No. 459,504, filed September 24, 1942, now U. S. Patent 2,409,012, granted October 8, 1946. The essential feature of the present invention resides in the means which are provided for distinctly separating the signals of stations whose frequencies are close together. This is accomplished generally by modifying the usual linear rate at which the scanning receiver is made to sweep across the band of frequencies.

An important feature of the invention lies in the system for generating a band spread pulse of proper character and combining it with the normal sawtooth sweep voltage so as to modify the normal linear sweep velocity. One result of this system is to slow up the sweep speed at one point at the sacrifice of accelerating it at another point. If the decelerated range occurs in a congested part of the band where there are present a plurality of signals, this will give the narrow band intermediate frequency section of the scanning receiver an opportunity to produce a much higher degree of discrimination.

A more detailed description of the invention follows in conjunction with a drawing, wherein:

Figs. 1a, 1b and 1c, taken together, diagrammatically illustrate a specific embodiment of the invention;

Fig. 2 graphically illustrates the manner in which the tuning of the recording receiver is stopped at the particular portion of the frequency spectrum being scanned at which the newly found signals appear;

Fig. 3 graphically illustrates the operation of the 360° phase shifter of Fig. 1; and

Fig. 4 graphically illustrates the manner in which a band spread pulse of proper character is combined with the normal sawtooth sweep voltage so as to modify the normal linear sweep velocity.

In Fig. 1 of the drawing, there is shown a scanning receiver of the type generally described in my U. S. Patent 2,409,012. In fact, the circuit elements shown within boxes and labeled "Superheterodyne receiver," "Reactance tube," "#1 comparator," "#2 comparator," "#1 phase shifter," "#2 phase shifter," "#1 pulse generator," "#2 pulse generator," "#3 pulse generator," "Amplifier," "Motor control," "360° phase shifter" and "Monitor" are generally the same as those employed and described in my copending application supra. What is new, however, and forms the essence of the present invention is the addition of apparatus labeled "#1 band spread generator," "#4 phase shifter," "#2 band spread

pulse generator," "#5 phase shifter," and the "Combining unit." These new circuit elements function to alter the sweep rate of the scanning superheterodyne receiver in the vicinity of a pulse from a known station.

Referring to Figs. 1a, 1b and 1c in more detail, there is shown a superheterodyne receiver 1 (Fig. 1a) indicated diagrammatically in box form. The heterodyne oscillator of the receiver (not shown) has its frequency controlled by a parallel tuned circuit 2. The receiver 1 is designed to receive telegraph signals, and is provided with a suitable tone keying circuit for supplying keyed tone signals corresponding to the marking intervals of the received telegraph signals. These keyed tone signals appear in the output circuit 3 of the superheterodyne receiver for subsequent use in the comparator device 4 (Fig. 1b) to be described in more detail later. For causing the receiver to periodically scan a predetermined portion of the radio frequency spectrum, there is provided a reactance tube circuit 5 of a well-known type, whose anode is connected to the tuned oscillatory circuit 2 of the heterodyne oscillator of the receiver, and whose control grid is connected to the output of a sweep device 6 which generates sawtooth waves. Since the reactance tube circuit 5 is well known in the frequency modulation art for providing a variable reactance output dependent upon the modulating voltages applied to the grid of the tube, it is not believed necessary to describe this circuit further. The sweep device 6 for generating sawtooth oscillations comprises, in the particular embodiment shown, a gaseous tube 7 which is arranged to rapidly discharge the condenser 8 through the space path of the tube after the charge on the condenser 8 has reached a critical value. Normally, the condenser 8 is linearly charged from the positive terminal of a source of potential B+ through a constant current limiting pentode 9. A negative bias is placed on the grid of triode 7 by battery 100. When the voltage on condenser 8 reaches a critical value which occurs when the positive voltage on condenser 8 overcomes the negative bias on the grid of tube 7, a discharge path is established through gas triode 7. A variable resistor 101 controls the linear rate of charge of the condenser 8. A sixty cycle synchronizing source, labeled as such, assures the breakdown of the gas tube 7 at a desired point in the cycle of operations. The output of the sweep device 6 is connected through lead 10 to the grid of the reactance tube 5 to apply sixty sawtooth waves per second to the reactance tube 5. As a result of this, the superheterodyne receiver will be caused to scan at a substantially uniform rate a predetermined portion of the radio frequency spectrum, after which the receiver will return to normal and repeat the scanning operation at the rate of sixty complete scanning operations per second. The range of the band of frequencies to be swept or scanned by the superheterodyne receiver is determined to a large extent by the magnitude of the sawtooth variations of the sweep circuit, and the position of the band in the spectrum is adjustable by the usual controls in the receiver.

A multiplicity of blank-out pulse generators with their respective associated phase shifters (note: Fig. 1b) are herein designated by the legends "#1 pulse generator" and "#2 pulse generator." Although only two generators are shown, there are usually provided as many pulse generators as there are known stations in the

frequency band to be scanned whose signals are to be blanked out. If, in the operation of the system, there are more pulse generators than known stations, the excess number of pulse generators may be rendered inoperative. All blank-out pulse generators have their outputs connected in parallel to the lead 21. Since the pulse generators are identical in construction and operation, it is deemed necessary to describe only one of these, let us say the #1 pulse generator.

This blank-out pulse generator is supplied with energy from the sixty cycle synchronizing source over leads 11 through phase shifter 13. The phase shifter consists of a sixty cycle transformer whose primary winding is connected to the reversing switch 12 and whose secondary winding has shunted across it a condenser and variable resistor 24. The junction of the condenser and variable resistor is connected to the grid of a gaseous discharge device 14 (sometimes known as a "Thyratron"). The center point of the secondary winding of the sixty cycle transformer is connected to a bias resistor 15 which supplies negative bias for the grid of the gas tube 14. The condenser 16 across the gas tube 14 is arranged to be charged through the variable resistor 17 and to be discharged through the space path of the tube at a sixty cycle rate. The voltage from condenser 16 is supplied to a trigger circuit 18 composed of a pair of vacuum tube triodes 19 and 20. Normally, tube 20 is in a state of conduction and tube 19 non-conducting. When a pulse is impressed on the grid of tube 19 from condenser 16, the state of conduction of the two tubes 19 and 20 is reversed. These two tubes, in effect, comprise a trigger circuit which always tends to be restored to the condition where 19 is non-conductive and 20 is conductive. This restoration takes place at a short interval after conduction starts in tube 19, and is determined by the values of resistor 62 and condenser 63. When tube 19 becomes conducting, its plate potential immediately drops for the duration of the conduction period, as a result of which a pulse of negative polarity is fed via lead 21 to the comparator 4. At this time, when tube 19 becomes conducting, tube 20 will become non-conducting by virtue of the regenerative nature of the feed-back circuit of the trigger arrangement. The value of condenser 63 and the value of resistor 62 determines the time of conduction of tube 19 and hence the time of duration of the pulse impressed on lead 21. Cathode resistor 64 furnishes the common bias for the grids of both tubes 19 and 20.

The particular time of occurrence or position in the sweep cycle of the pulse obtainable from the trigger circuit 18 is controlled by adjustment of the phase shifter 13 and more specifically by the adjustable resistor 24 in the phase shifter. Since the adjustment of the resistor 24 of the phase shifter will only provide a variation in position of the pulse obtainable from the trigger 18 over substantially one-half or 180° of the sweep cycle, it thus becomes necessary to provide means for changing the position of the pulse in the sweep cycle over the entire cycle and this is accomplished by means of the reversing switch 12 which by its operation enables the adjustable resistor 24 of the phase shifter to control the position of the pulse obtainable from the trigger circuit 18 for any desired portion of either of the two halves of the cycle. It should at this time be understood that the adjustment of the position of the pulse obtainable from the pulse

generator is important because this position must be made to correspond to the position of the signal received from a known station in order to be able to blank-out the signal from the known station in the comparator 4. The adjustment of the duration of the blank-out pulse obtainable from the pulse generator is also important because the duration of the blank-out pulse must correspond to the duration of the signal received from the known station. The appearance of a blank-out pulse in the lead 21 will cause a relatively negative pulse to be applied to the comparator 4 for reasons which appear hereinafter.

As for the comparator 4 (Fig. 1b), this circuit comprises a pair of push-pull vacuum tube amplifiers 25 and 26 operating as class B; that is, normally biased to a point of anode current cut-off. The grids of these amplifiers are connected to opposite terminals of the secondary winding of a single input transformer 27 which is designed to pass the keyed tone appearing in the output circuit 3 of the receiver. The combination of resistors 160 and 161 gives the proper bias for the grids of the tubes 25 and 26 by raising the cathode potential to a desired amount above ground potential. By making the cathode positive, the grid is, in effect, made to be negative since the grid is tied down to ground potential. The anodes of the tubes 25 and 26 of the comparator 4 are connected in push-pull to the opposite terminals of audio output transformer 28, also designed to pass the tone. In the operation of the comparator 4, the vacuum tubes 25 and 26 will normally pass the alternate half cycles of the tone appearing in the transformer 27. However, the application of a negative blank-out pulse from one of the pulse generators over lead 21 will supply an additional negative bias to the grids of the tubes 25 and 26 which will prevent these tubes from passing current during the application of the blank-out pulse even in the presence of tone signals on input transformer 27. It will thus be seen that by means of the pulse generators it is possible to prevent the comparator 4 from passing current at any particular time and for any desired duration in any sweep cycle.

The output of comparator 4 is passed on to a recorder coil 65 (note Fig. 1c) which is associated with a loop of continuously moving magnetic tape 66. In this way the coil 65 registers signals on tape 66 in response to impulses which pass through comparator 4 and which are representative of a new signal.

The magnetic tape 66 is continuously driven in the direction indicated by the arrow by motor M' which is synchronously controlled by the same sixty cycle source which is associated with the sweep device 6. Loop 66 is exactly two sweep cycles in length; that is, the relative speeds of scanning of the receiver 1 and rotation of loop 66 must be such that the loop of tape 66 makes one complete circuit while the receiver 1 sweeps through a complete sweep cycle twice. During each sweep cycle of the receiver 1, a desired portion of the radio spectrum to be studied will be scanned and the receiver will be ready for the next sweep. A magnetic pick-up coil 67 is located half way around the tape 66 from the recording coil 65 and spaced one complete sweep cycle apart from coil 65 along the tape.

The pick-up coil 67 is connected to a switch 68 which in one position (namely the left) can erase the signals recorded on the tape 66, while in the other position (namely the right-hand position) passes the signals picked up from loop 66

to the amplifier 69. The output of the amplifier 69 is in the form of amplified pulses which have been picked up by the pick-up coil 67. These amplified pulses are passed on to a second 5 comparator 90 where they are rectified in tube 70 and applied to the anode of a triode 71. The purpose of comparator 90 is to prevent noise pulses from being passed on to operate the motor control circuit 80. This second comparator 10 includes a pair of rectifier tubes 70 and 72, and also a vacuum tube triode 71.

Any newly found signal will appear in the output of transformer 28 of the comparator 4 in the form of keyed tone pulses. This newly found 15 signal will be rectified in rectifier 72 of the second comparator and impressed upon the grid of the vacuum tube triode 71, at the same time that the signal is applied to the recorder coil 65. If this newly found signal has appeared in a 20 previous sweep cycle, it will have been registered on tape 66. When an impulse impressed on recorder coil 65 corresponds in time to an impulse registered on the tape 66 and simultaneously picked-up by coil 67, it will be seen that both 25 rectifiers 70 and 72 will at the same time be impressing positive potentials on both the grid and anode electrodes of tube 71. This condition will cause the tube 71 to pass current, as a result of which a pulse of voltage will be taken off the 30 cathode of triode 71 and passed on to the motor control circuit 80. The comparator 90 in this way serves to prevent noise from entering the motor control circuit. Since noise is fortuitous and random in character, seldom will it appear 35 twice in succession at times one complete cycle apart. Thus, if noise appears only once, there will be a pulse corresponding to this noise which will pass rectifier 72 and be impressed upon the grid of vacuum tube 71, but there will not be 40 a correspondingly timed pulse picked up by coil 67, amplified by 79, rectified by tube 79 and impressed on the anode of 71. The application of a pulse solely to the grid or to the anode of tube 71 will not cause this tube to pass current since 45 the circuit elements are so constructed and designed that there is required the application of pulses to the anode and to the grid of tube 71 simultaneously in order to cause this tube to pass current. Thus, only when a newly found 50 signal appears (which of course will be repeated during consecutive sweeps of the receiver) will the comparator 90 pass current to the motor control circuit.

The motor control circuit 80 (Fig. 1c) comprises two gas triodes (Thyratrons) 78 and 79, both of which are normally non-conductive. It should be noted that the path to operate the grid of tube 78 comprises connection 75 and includes the armature and normally closed contact 55 of relay 77. Relay 77 is in the cathode circuit of gaseous conduction tube 78 while a relay 76 is in the anode circuit of gaseous conduction tube 79. The application of a positive pulse from the 60 comparator 90 to the lead 75 will cause a voltage to pass through the contacts of the relay 77 and ignite tube 78 of the motor control circuit. This will cause tube 78 to pass current and operate relay 77. The operation of the relay 77 will break the path from the lead 75 to the grid of the 65 tube 78 and will connect this path to the grid of tube 79. At the same time, the operation of relay 77 will connect ground to lead 74 to operate the "spotting motor" M, which, in turn, causes the conventional recording receiver 91 to become 70 operative and change its tuning over the same 75

band of frequencies which is being scanned by the superheterodyne receiver 1.

The manner in which the tuning of the receiver 91 over the band of frequencies being scanned is stopped at the exact point at which the newly found station appears in the spectrum being scanned will now be described. Receiver 91 is initially tuned to one end of the band of frequencies being investigated. The tripping of the motor control circuit 80 and the consequent operation of the motor M starts the receiver 91 and causes the frequency of the receiver 91 to which it is tuned to change under the drive of the spotting motor. The motor M also drives the phase shifter 81 over shaft 182 simultaneously with the change in tuning of receiver 91. This phase shifter 81 is a 360° motor driven phase shifter which is synchronously controlled over leads 82 from the same 60 cycle synchronous source which synchronizes the sweep device 6 and the pulse generators, as well as synchronizing the motor M'. The phase shifter 81 includes a pair of potentiometers 92 and 93 with continuous resistance elements and sliders 94 and 95 that can rotate 360°. The resistance elements are tapped every 90°. The two potentiometers are ganged and arranged so that, if corresponding taps are in line, the sliders 94 and 95 are mutually perpendicular. A voltage from synchronizing leads 82 is applied through a transformer 97 to terminals C and D on potentiometer 93, and the same magnitude of voltage applied through 90° phase shifter 98 and transformer 99 to terminals A and B on the other unit 92, but shifted 90° with respect to the voltage applied to terminals C, D. The output of the 360° phase shifter 81, taken from the sliders 94 and 95 is fed through transformer 96 to the #3 pulse generator.

The vector diagram of Fig. 3 shows the voltages at the taps of the two resistive elements. Points O and O' on both elements are all at the same potential or reference point as shown on the vector diagram. As slider 94 rotates, the magnitude but not the phase of the voltage which it picks up varies from vector OA to vector OB and back again to OA. This is an amplitude variation with no variation in phase. Likewise the voltage from slider 95 varies from OC to OD and back to OC. The output taken through transformer 96 is the vector sum of the slider voltages. This output, indicated as vector OR will have a locus of variation as indicated by the dotted line on Fig. 3. As the common shaft 182 of the potentiometers 92 and 93 is rotated, the phase of vector OR, representing the output voltage, will advance continuously in the direction of the arrow from its initial or reference position OC and for one complete revolution of this shaft 182 the phase of the output voltage will change by 360°.

A short pulse generator labeled "#3 pulse generator" is provided which is identical in construction and operation to the circuits of the #1 pulse generator and #2 pulse generator. Initially, the pulse developed by this #3 pulse generator appearing in lead 83 has a phase as indicated by the pulse in line B of Fig. 2. As the phase shifter 81 is driven by the motor M, the position of the pulse in the output lead 83 of the #3 pulse generator advances over the sweep cycle until such time as it coincides in time with a pulse of the newly found station. This is indicated in line C of Fig. 2. The pulses in lead 83 coming from #3 pulse generator are impressed on the grid of tube

79 of the motor control circuit 80. As long as the pulse of the newly found signal appearing in lead 75 does not coincide in time with the pulse appearing in lead 83, tube 79 will remain non-conductive. When, however, a pulse in lead 83 coincides in time phase with a pulse appearing in lead 75 from the output of comparator 90, it will be seen that both pulses will be impressed on grid of gas triode 79 simultaneously. Since these pulses are positive, the simultaneous appearance of both pulses in leads 75 and 83 will ignite tube 79, as a result of which relay 76 will operate. The operation of relay 76 will break the anode circuit of tube 78, thus extinguishing the arc in tube 78 and causing relay 77 to release. It is assumed, of course, that the manually operated switch 84 supplying positive polarizing potentials to gas tubes 78 and 79 is normally closed during all this time, it being opened only when it is desired to restore the complete circuit to normal. The release of relay 77 will open its right-hand contact, thus stopping the motor M at a point which corresponds to the point at which the newly found signal appears in the frequency spectrum. The tuning of the receiver 91 will be stopped at this point in the radio frequency spectrum. The standard code recorder 85 which operates continuously from the time that receiver 91 is made to be operative by the motor M, will now record the signals of the newly found station collected by receiver 91 over antenna 192. Putting it in other words, it will be seen that since the phase of the pulse from comparator 90 is an indication of the position of the new station in the spectrum, and the phase of the pulse from #3 pulse generator is an indication of the frequency of the receiver 91, the matching of these pulses will match the frequency of receiver 91 to that of the desired signals. It should be noted that although receiver 91 is tuned to the frequency of the newly found signal within the spectrum being scanned, the superheterodyne receiver 1 will continue scanning.

The purpose of the monitor circuit 55 is to enable the operator to make suitable adjustments in the system. This monitor consists of a cathode ray oscilloscope 54 having horizontal deflection plates 56 and vertical deflection plates 57, together with an associated rectifier 58 for applying rectified pulses to one of the vertical deflection plates 57. The anode of the rectifier 58 is connected to the armature of a switch 59 by means of which the rectifier can be connected either directly to the keyed tone output circuit 3 of the superheterodyne receiver by means of lead 60, or directly to the output of the comparator device 4 by means of lead 61. Thus, the attendant is able to observe at a glance by suitably operating the switch 59, the appearance of the pulses in the output of the superheterodyne receiver 3 and also the appearance of the pulses in the output of the comparator 4. If the system is properly adjusted, the key tone pulses appearing in the output of the superheterodyne receiver 1 will not appear in the output of the comparator 4, except for the signals corresponding to those from the unknown or newly found station.

The apparatus so far described in detail is generally the same described in my U. S. Patent 2,409,012. The new apparatus constituting the gist of the present invention comprises the addition of band spread pulse generators and associated phase shifters, herein labeled as such (103—104), and also combining unit 112. These will now be described in greater detail.

The band spread pulse generator 103 (Fig. 1a) with its associated phase shifter 104 is similar to the #1 pulse generator and phase shifter 13, except for the difference in the tripping circuit in the band spread pulse generator and the reshaping circuit associated with the cathode of one of the tripping tubes of 103. The tripping circuit of 103 comprises two triode vacuum tubes 19' and 20', the electrodes of which are respectively interconnected (as shown). The operation of this tripping circuit of 103 is similar to the operation of the tripping circuit 18 of the #1 pulse generator. However, the output pulse generated by the pulse generator 103 is derived from the cathode of tube 19' and passed over lead 105 to the pulse reshaper consisting of condenser 106, inductance coil 107, condensers 108, 109 and resistor 110. In order that this pulse reshaping circuit function properly, it is essential or necessary that it be driven from a low impedance source and this is accomplished by connecting the lead 105 to the cathode of tube 19'. It should be noted that the tripping circuit of 103 differs from the tripping circuit 18 of #1 pulse generator in employing separate cathode biasing elements for the two tubes instead of a common cathode biasing circuit. This is because it is desired to obtain a low impedance output from tube 19' only.

The output from the pulse reshaper is taken from resistor 110 by means of a tap associated with lead 111 which extends to the grid of a vacuum tube 115 constituting the combining unit 112.

The combining unit 112 is used for the purpose of injecting the special band spread pulses into the sawtooth wave form employed for the scanning superheterodyne receiver. The output from the combining unit 112 is taken from the anode of the vacuum tube 115 and applied through condenser 113 to the lead 10 extending to the reactance tube circuit 5. In the operation of the system as described above, a square pulse is developed across the cathode resistor of triode 19' in a manner similar to that described for the #1 pulse generator. This square pulse is applied through lead 105 to the pulse reshaper where it is modified from essentially square form to a sinusoidal form, as indicated by line K of Fig. 4. This modified pulse is then applied by lead 111 to the grid of tube 115 of the combining unit 112, the output of which is further combined with saw-tooth voltage in lead 10 emanating from the sweep device 6. The combined wave form in lead 10, which is the resultant of the sawtooth wave from sweep device 6 and the modified sinusoidal or band spread pulse from the combining unit, produces a modified wave form for utilization by the reactance tube circuit.

The manner in which the band spread system of the invention functions may be understood better by referring to the diagrams of D to K, inclusive, of Fig. 4.

For purposes of explanation, it will be assumed that the normal output of scanning receiver 1 appears as wave form D of Fig. 4, in which pulse 37 is the only signal originally present (corresponding to the signal from a known station) and pulse 36 represents a signal which is to appear later. Wave form E is the linear saw-tooth voltage developed by the sweep device 6. As indicated previously, it is desirable to suppress this normal or original pulse 37 so that the sudden appearance of a new signal such as 36 can be detected. Although pulses 36 and 37 are shown well separated for purposes of expla-

nation, they might in actual reception be combined into one irregular broad pulse because of the unavoidable poor resolving power of the narrow band intermediate frequency section of the receiver when a high sweep velocity is used.

This invention proposes to alter the sweep rate in the vicinity of pulse 37 according to the modified saw-tooth wave G. A pulse 38 represented in line F, having a wave form similar to one cycle of a standard sine wave, is combined with saw-tooth wave E to give the result shown in line G. In the region a—b, the normal constant slope of the saw-tooth has been decreased to a much lower value and during this interval of time the sweep rate of the superheterodyne receiver will be less than the normal value. In the region b—c, however, the rate is much higher than normal and in c—d it is below normal again.

By comparing the phase of this band spread pulse 38 with that of signal pulse 37, it will be seen that the receiver sweep speed has been reduced on both sides of this signal pulse but increased during most of the normal pulse duration. It can be said that in the marginal areas around pulse 37 (new pulse 36 lies in one of them) velocity or sweep band spread has been accomplished while band compression has been produced during most of the original period of this pulse. As a result of this modification in sweep speed of the superheterodyne receiver, the original panoramic picture of wave form D will be reduced to that of wave form H. The new station pulse 36 will appear in the output of the receiver as a much larger pulse 39 because of the better narrow intermediate frequency section resolution or build-up at slower sweep speed and pulse 37 will be reduced as shown to pulse 40 because of the poorer narrow band intermediate frequency response at the high sweep rate.

As explained previously, the remaining pulse 40 may be balanced out of the #1 comparator 4 output by means of a locally supplied counter or blank out pulse from #1 pulse generator.

When a new signal 36 appears on a frequency very close to an original signal 37, it will be well separated therefrom (as shown by pulse 41 of the wave form I) and can be detected as described in the disclosure referred to.

In Fig. 1 a multiplicity of band spread pulse generators #1 and #2 are shown, so that this feature may be had for each of the original signals found in the band. It is also quite possible to have band spread pulses different in wave form from that shown in wave form F, Fig. 4, which was given only by way of example.

Lines J and K of Fig. 4 are given as a suggestion of a circuit operation for developing a wave form similar to that of pulse 38, line F. If a rectangular or square pulse such as that of wave form J is applied to the input of the wave reshaper circuit of Fig. 1, a single cycle damped sinusoid like that of wave form K will result if elements 106, 107, 108, 109 and 110 of Fig. 1 are of the proper nature relative to each other.

The reason why the superheterodyne receiver can give a much higher degree of discrimination between closely spaced signals if the usual linear scanning rate of the receiver is modified, may be better understood by an appreciation of the principle that the ability of the narrow band pass intermediate frequency selective circuit in the receiver to build up a signal is generally inversely proportional to the sweep rate; i. e., the slope of the saw-tooth wave. The rate of sweep which

is proportional to the slope of the saw-tooth wave is suitably chosen, in accordance with the invention, to conform with such factors as the width of the band of the frequencies to be scanned and the scanning frequency. Hence, a slower sweep rate or a narrower band of frequencies swept over enables a signal to produce a greater response in the receiver output compared to a faster sweep rate.

The terms "band spread" and "band compression" are here employed to refer respectively to the increase in scanning rate or decrease in scanning rate during which a particular portion of the frequency spectrum being scanned can alter the receiver response. These terms should not be construed to refer to a broadening or a narrowing of the frequency spectrum being scanned but rather to a momentary modification of the scanning rate.

A general description of the operation of the system as a whole will now be given. Sweep device 6 causes the frequency of hunting receiver 1 to sweep over a given predetermined band width. The panorama of signals in this band will be observed on cathode ray monitor 55 as the receiver sweeps repeatedly over the band. Before the signals from the known stations in the band being scanned are blanked out, the band spread pulses are developed or set up, which improve or increase the receiver response characteristic at the margins of the signals from the known station. The proper adjustment of the band spread generator is observed on the visual monitor by connecting the monitor to the output of the scanning receiver through switch 59 or to the lead 10 extending to the reactance tube circuit by way of switch 120. Then, I adjust the blank out pulse generators #1 and #2 and additional such units as needed so that the signals from the known stations cannot be observed on the monitor oscilloscope when it is connected to #1 comparator output. However, it is important that the width of the blank out pulses be no greater than necessary to wipe out the known signals, otherwise an unknown signal suddenly appearing very close in the frequency spectrum to the known signal might also be wiped out by the blank-out generator. The output of comparator 4, which is registered on magnetic loop 66, will then consist only of noise pulses, if present, and any new signals which may appear. In the case of random noise pulses, comparator 90 will not respond. In the case of signals from a new station, however, these are registered on the tape and comparator 90 will function because of the presence of simultaneous pulses from the receiver 1 and pick-up coil 67. The comparator 90 passes the newly found signals on to motor control unit 80 which places spotting motor M into operation for simultaneously rotating phase shifter 81 and moving the tuning of recording receiver 91. As the motor M rotates, the phase of the local pulse generated by #3 pulse generator will advance and finally be in time phase with the received pulse coming over lead 75 at which time motor M will stop, thus causing the tuning of the recording receiver 91 to stop in the proper position for this last receiver to pick-up the new signals and record them in apparatus 85. Receiver 91 will remain tuned to the frequency of the new signals until an attendant, or other means not indicated, changes the tuning. In summation, the operation

consists of the following fundamental steps: (1) A given portion of the radio spectrum is repeatedly scanned for the presence of signals; (2) all signals in the selected portion of the spectrum are investigated and the receiver response characteristic at the margins of the signals from known stations improved, after which the known signals are balanced out by locally generated pulses; (3) the appearance of new signals is investigated and if they persist (4) a new receiver is automatically tuned to the frequency of the new signals so that they may be recorded, and (5) the effect of noise peaks is eliminated.

To restore the entire system to normal, in order to hunt for another new station, the registrations on the magnetic tape 66 should be erased by throwing the switch 68 to the left. The opening of switch 84 in the motor control circuit will restore the motor control circuit to normal. By means of a manual adjustment (not shown) in the receiver 91, this receiver can be retuned to the point of origin of the frequency spectrum being scanned by the receiver 1. It should, of course, be understood that when the receiver 91 is made to be operative to be tuned over the frequency band by motor M, the width of the tuning band of the receiver 91 corresponds to the frequency spectrum scanned by superheterodyne receiver 1. The 360° phase shifter 81 must also be restored to normal and this can also be done manually by means not shown. In order to place this system in operation again, the band spread generators and the pulse generators #1 and #2 are reset or readjusted to serve their respective functions, during which time the switch 68 should be in a position to continue erasing and after which time the switch 68 should be thrown to the amplifier position. The switch 84 in the motor control circuit should now be closed.

The present invention provides for altering the normal rate of scanning of the hunting superheterodyne receiver and has the following advantages: It improves the receiver response of the intermediate frequency amplifier selective circuits of the receiver, and enables the receiver to be more efficaciously utilized at those portions of the frequency spectrum to be studied. In this way, the invention permits very rapid scanning of those portions of the frequency band where it is not expected to find new signals, but slow scanning on portions of greater interest in this band.

It should be understood that it is within the contemplation of the invention to change the scanning rate and the width of the portion of the radio spectrum to be scanned at the will of the operator. The scanning rate can most easily be changed by changing the fundamental frequency of the sweep device and the pulse generators.

What is claimed is:

1. The combination with a receiver, of circuit apparatus for periodically and continuously tuning said receiver to scan a desired radio frequency band, said circuit apparatus including electronic means for changing the speed of scanning over different parts of the band, as the receiver tunes from one end of the band to the other end, without changing the mean scanning velocity, to thereby produce different receiver response characteristics over different parts of the band being scanned.

2. The combination with a receiver, of circuit

apparatus for periodically and continually tuning said receiver over a desired radio frequency band, said circuit apparatus including means for tuning the receiver at a substantially linear rate over one part of said band and electronic means for modifying the substantially linear rate of tuning over another part of said band as the receiver tunes from one end of the band to the other end, to thereby produce a receiver response characteristic over said one part of the band which is different from the receiver response characteristic over said other part of the band.

3. In a receiving system, a receiver, means including an oscillator of saw-tooth waves for repeatedly tuning the receiver at a substantially linear rate over a selected band of frequencies, circuit apparatus for producing substantially sinusoidal waves of shorter duration than said saw-tooth waves but of the same frequency, and means for combining said sinusoidal waves with said saw-tooth waves to modify the normally substantially linear rate of tuning the receiver over said band, to thereby change the response character of the receiver over different portions of said band of frequencies.

4. In a receiving system, a receiver, electron discharge device apparatus for repeatedly tuning the receiver at a substantially linear rate over a selected band of frequencies, a wave form oscillator synchronized in frequency with the tuning rate of said receiver, and means for combining the output of said oscillator with the output of said electron discharge device apparatus for modifying the normally substantially linear rate of tuning said receiver at any desired point over the selected band of frequencies being scanned, to thereby change the response character of the receiver at that point compared to other points in said selected band of frequencies.

5. In a receiving system, a receiver, an electron discharge device coupled to the output of said receiver, means for periodically tuning the receiver over a selected band of frequencies, a local pulse generator producing pulses of predetermined polarity, means for combining the pulses from said generator with the output of said receiver, whereby a signal from a known station appearing in the output of said receiver may be prevented from passing through said discharge device, and means for modifying the rate of tuning of the receiver at that portion of the band at which the signal from the known station appears.

6. In a receiving system, a receiver, an output circuit for said receiver, means for periodically tuning the receiver over a selected band of frequencies, a local pulse generator, a circuit for adjusting the position of the pulse produced by said generator during the cycle of operation, means for combining the pulses from said generator with the output of said receiver, whereby a signal from a known station appearing in the output of said receiver may be prevented from passing through said output circuit, and means for modifying the rate of tuning of the receiver at and adjacent to that portion of the band at which the signal from the known station appears.

7. In a receiving system, a receiver, an output circuit for said receiver, means for periodically tuning the receiver over a selected band of frequencies, a local pulse generator producing unidirectional pulses, a circuit for adjusting the position of the pulse produced by said generator during a cycle of operation, means for combining the pulses from said generator with the output

of said receiver, whereby a signal from a known station appearing in the output of said receiver may be prevented from passing through said output circuit, and means for modifying the rate of tuning of the receiver at those points in the band corresponding to the marginal edges of the signal of the known station.

8. In a receiving system, a receiver, a utilization circuit for said receiver, means for periodically tuning the receiver over a selected band of frequencies, a local pulse generator, means coupled to said pulse generator and responsive to the pulses produced thereby for preventing a signal from a known station appearing in said receiver from being passed on to said utilization circuit, and means for decreasing the normal rate of tuning of the receiver at those points in the band corresponding to the marginal edges of the signal from the known station.

9. In a receiving system, a receiver, a utilization circuit for said receiver, means for periodically tuning the receiver over a selected band of frequencies, a local pulse generator, means coupled to said pulse generator and responsive to the pulses produced thereby for preventing a signal from a known station appearing in said receiver from being passed on to said utilization circuit, and means for decreasing the normal rate of tuning of the receiver at those points in the band corresponding to the marginal edges of the signal from the known station and for increasing the normal rate of tuning of the receiver at that point in the band corresponding to the center of the signal from the known station.

10. In a receiving system, a receiver, means including a saw-tooth oscillator for repeatedly tuning the receiver in substantially linear manner over a selected band of frequencies, a local pulse generator producing unidirectional pulses of predetermined polarity, said pulses having a frequency the same as said saw-tooth oscillator, a circuit for controlling the time of occurrence of the pulses produced by said local pulse generator during the cycle of operations, and a circuit connecting the output of said generator with the output of said saw-tooth oscillator, whereby the normally substantially linear rate of tuning of said receiver can be modified at any desired portion of said band with a consequent modification of the character of the receiver response at that point.

11. In a receiving system, a receiver, means including a saw-tooth oscillator coupled to an electrode of a reactance tube for tuning the receiver in substantially linear manner over a selected band of frequencies, a local pulse generator producing pulses having a frequency the same as said saw-tooth oscillator, a circuit for controlling the time of occurrence of the pulses produced by said local pulse generator, and an electron discharge device combining unit coupling the output of said generator to the same electrode of the reactance tube to which said saw-tooth oscillator is connected, whereby the normally substantially linear rate of tuning of said receiver can be modified at any desired portion of said band with a consequent modification of the character of the receiver response at that point.

12. In a receiving system, a receiver, a utilization circuit for said receiver means including a saw-tooth oscillator for periodically tuning the receiver over a selected band of frequencies, a local pulse generator, means coupled to said pulse generator and responsive to the pulses pro-

duced thereby for preventing a signal from a known station appearing in said receiver from being passed on to said utilization circuit, another local pulse generator, a network in the output of said last pulse generator for reshaping the wave form of the pulse generated by said last pulse generator, means for synchronizing the pulse rate of both said pulse generators with the frequency of said saw-tooth oscillator, and a circuit for combining the output of said network with the output of said saw-tooth oscillator for modifying the rate of tuning the receiver at a desired point in the band of frequencies being scanned.

13. In combination, a receiver, a cathode ray device coupled to the output of said receiver, a source of waves coupled to said device for producing a linear sweep of the ray of said device and also coupled to said receiver to periodically tune said receiver over a selected band of frequencies, a wave form oscillator having a frequency the same as said source, and means for combining the output of said oscillator with said source for changing the normal rate of tuning of said receiver and for modifying the linear rate of sweep of said ray as the ray moves in one direction from one end to the other end of its path of travel.

14. In a receiving system, a receiver, means for periodically tuning the receiver over a selected band of frequencies, a vacuum tube coupled to the output of said receiver, a generator producing unidirectional pulses of relatively negative polarity, a connection from the output of said generator to said vacuum tube, whereby the pulses supplied by said generator bias said vacuum tube to prevent the passage of signals therethrough for the duration of the pulses, a circuit for adjusting the position of said pulses during the cycle of operation, and means for modifying the rate of tuning of the receiver at a desired point in the selected band of frequencies being scanned.

15. In a receiving system, a receiver, means for periodically tuning the receiver over a selected band of frequencies, a vacuum tube coupled to the output of said receiver, a generator producing unidirectional pulses of relatively negative polarity, a connection from the output of said generator to said vacuum tube, whereby the pulses supplied by said generator bias said vacuum tube to prevent the passage of signals therethrough for the duration of the pulses, a circuit for adjusting the position of said pulses during the cycle of operation, and means including another pulse generator for modifying the rate of tuning of the receiver at a desired point in the selected band of frequencies being scanned.

16. In a receiving system, a receiver, a utilization circuit for said receiver, means for periodically tuning the receiver over a selected band of frequencies, a local pulse generator operating in synchronism with said means, a circuit for adjusting the position of the pulse produced by

said generator during a cycle of operations, means coupled to said pulse generator and responsive to the pulses produced thereby at predetermined positions during the cycles of operation for preventing signals from known stations from being passed on to said utilization circuit, and means for modifying the rate of tuning of the receiver at a desired point in the selected band of frequencies being scanned.

17. In a receiving system, a tunable receiver, means including an oscillator of triangular-shaped waves for repeatedly tuning the receiver at a desired rate over a selected band of frequencies, a wave form oscillator operating in synchronism with said first oscillator for producing wave forms of shorter duration than said triangular-shaped waves but of the same frequency, means for adjusting the position of the wave form produced by said wave form oscillator during a cycle of operation, and means for combining said wave forms with said triangular-shaped waves to modify the normal rate of tuning the receiver over said band, to thereby change the receiver response characteristic over different portions of said band of frequencies.

18. An intelligence reproducing system comprising a signal source including signal recording means for repeating the signals, an intelligence reproducer, and control means intermediate said signal source and said reproducer, said control means including means solely responsive to a predetermined periodic duplication of a signal from said source for activating said reproducer, and a band spread means including a pulse generator coupled to said signal source for separating adjacent signals, said generator including means for producing a rectangular wave pulse and means for converting said rectangular wave pulse to a sinusoidal wave.
